ELECTRIC GRILL

Burton E. Shaw, Cambridge, and Roger K. Lee, Jr., Watertown, Mass., assignors to Electronics Corporation of America, Cambridge, Mass., a corporation of Massachusetts

Filed Oct. 26, 1959, Ser. No. 58,073

Term of patent 14 years

(Cl. D81—10)

We claim:

The ornamental design for an electric grill, substantially as shown.
